UNITED STATES PATENT OFFICE.

ANNA M. BISSIG, OF CITY POINT, WISCONSIN.

DESIGN FOR A WATCHCASE.

40,695.

Specification for Design.

Patented May 17, 1910.

Application filed March 12, 1910. Serial No. 549,065. Term of patent 7 years.

To all whom it may concern:

Be it known that I, ANNA M. BISSIG, a citizen of the United States, residing at City Point, in the county of Jackson and State of Wisconsin, have invented a new, original, and ornamental Design for Watchcases, of which the following is a specification, reference being had to the accompanying drawing, forming part thereof.

Figure 1 is a plan view showing one face

of the watch case, and, Fig. 2 is a similar view of the opposite face thereof.

I claim:

The ornamental design for a watch case, as shown.

ANNA M. BISSIG.
